UNITED STATES PATENT OFFICE.

HENRY J. HERBERT, OF DETROIT, MICHIGAN, ASSIGNOR TO UNITED STATES CHEMICO WOOD COMPANY, OF DETROIT, MICHIGAN, A CORPORATION OF MICHIGAN.

DESIGN FOR A BRUSH BACK AND HANDLE.

SPECIFICATION forming part of Design No. 35,576, dated January 14, 1902.

Application filed December 16, 1901. Serial No. 86,161. Term of patent 7 years.

To all whom it may concern:

Be it known that I, HENRY J. HERBERT, a citizen of the United States, residing at Detroit, in the county of Wayne and State of Michigan, have invented and produced a new and original Design for a Brush Back and Handle, of which the following is a specification, reference being had therein to the accompanying drawings.

Figure 1 is a plan view of a brush back and handle, showing my design; and Fig. 2 is an edge elevation thereof.

As shown in the drawings, the leading or material feature of my design consists in the tapering oval back portion A, merging into the tapering handle B and ornamented with

broken-vein-like corrugations. C is an enlargement at the lower end of the handle, likewise provided with similar ornamentation. The edge D of the back and handle is plain, as shown.

Having described my invention, what I claim as new, and desire to secure by Letters Patent, is—

The design for a brush back and handle as herein shown and described.

In testimony whereof I affix my signature in presence of two witnesses.

HENRY J. HERBERT.
